UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF HOLDER.

Application filed July 3, 1925. Serial No. 41,378.

This invention relates to loose-leaf holders particularly adapted to releasably clamp a sheet or a plurality of sheets between the back and cover thereof without the use of 5 empaling members such as rings, posts, thongs or the like.

The invention is especially directed to what is known in the art as a sheet holder and has for its primary object the provision 10 of a new and novel means for releasably retaining any number of sheets in the holder through the use of a resilient member which is also adapted to retain the elements of the binder in their assembled relation.

15 A further object of the present invention is to provide a novel means of forming the top and bottom elements of a loose-leaf holder whereby a special pivot pin may be interposed to perform a function not here- 20 tofore known.

25 An even further object of this invention is the contemplation of a leaf-clamping member which is adapted to hingedly support a cover as well as to perform the function of a clamping member to hold the leaves in place.

30 Many minor objects will appear during the course of the detailed specification referring to the accompanying drawing in 35 which similar reference numerals designate like parts throughout the several views. In the drawing:

Figure 1 is a perspective view of a loose-leaf holder made in accordance with this invention.

Fig. 2 is an enlarged detailed section taken on line II-II of Fig. 1.

Fig. 3 is an end view of the hinged portion of the holder showing the same in the 40 completely opened position and, in the dotted lines, in a position ready to receive additional sheets.

Fig. 4 is a broken cross section of the 45 resilient retaining member taken on line IV-IV of Fig. 2, and,

Fig. 5 is a perspective view of the split tube retaining member showing it removed from the holder.

The holder made in accordance with this 50 invention is preferably constructed of sheet metal such as aluminum, and must have a back and cover 6 and 7 respectively of a size to suit the particular size of sheet 8 to be used. These members 6 and 7 may be

stiffened as at 9, if desired, and should have 55 the corners rounded to afford a neat appearance.

Back 6 is formed to provide an arcuate channel portion 10 at its one end which is disposed on a plane above that of the major 60 portion of the back and which extends the entire width thereof to receive a pivot pin 11. This pin 11 is preferably made of wood and treated to cause the same to properly function as a smooth sliding surface for 65 arcuate channel portion 12 of leaf-clamping member 13. As shown in Figs. 2 and 3, pin 11 is interposed between arcuate channel portion 10 and 12 and is not directly connected thereto in any way. Furthermore, 70 the circumference of pin 11 is greater than the combined distance across the two arcuate channels and neither one nor both portions 10 and 12 are large enough to pass completely 75 around the pin 11.

To retain these members 6, 11 and 13 in the assembled relation, as well as to exert a leaf-holding pressure, a split-tube resilient member 14 may be used which engages the convex surface of arcuate channel portions 80 at points near where they join back 6 and leaf-clamping member 13. This member 13 at the edge opposite the arcuate channel portion 12 is curled upwardly and back upon itself to form a plurality of pintle barrels 85

15, spaced apart by notches 16 into which similarly constructed barrels 17 of cover 7 are adapted to be disposed to receive pintle 18 which passes through all barrels 15 and 17 to form a hinge as clearly shown in Fig. 90

1. This hinge permits of raising cover 7 when desired without dislodging sheets 8. The pressure exerted by member 14 upon leaf clamping member 13 normally holds it in the closed position as shown in Fig. 2 and 95 against any sheets 8 that might be lying upon back 6. To open or raise member 13, back 6 should be hinged back in the position shown in dotted lines of Fig. 3, and an upward leverage gained by causing the same 100 to engage shoulder 19. Thus, a pressure in the direction of the arrow (Fig. 3) will cause the forward or hinge end of member 13 to rise. To completely open the holder, the same pressure is carried back until top 105 7 and member 13 assume the position shown in full lines of Fig. 3. During these operations, arcuate channel portion 12 of member

13 is riding over the periphery of pivot pin 11 and member 14 is exerting a squeezing or inward pressure. When ends 20 and 21 of upper and lower arcuate channel portions 5 respectively meet, the opening action is stopped.

This particular construction has been found to be of value in connection with many forms of binders, and it is desired to 10 be limited in its use only by the scope of the appended claims.

What I claim is:

1. A loose-leaf holder comprising a back, leaf-clamping means supported by said back, 15 a pivot pin interposed between said back and said leaf-clamping means and resilient means for maintaining said back and leaf-clamping means in direct sliding engagement with said pivot pin, the ends of said 20 back and leaf-clamping means adjacent said pivot pin adapted to abut and limit movement therearound.

2. A loose-leaf holder comprising a back having an arcuate channel portion adjacent 25 its one end and extending the entire width thereof, a pivot pin co-extensive with said portion and seated therein, a leaf-clamping member having an arcuate channel portion adjacent one of its sides also adapted to directly engage said pivot pin, a cover hingedly connected to the other side of said leaf-clamping member and resilient means 30 engaging the arcuate channel portion of said back and clamping member along their entire length, each of said arcuate channels 35 being rebent whereby an edge of the channel of said leaf-clamping member abuts an edge of the channel of said back when the holder is in either the open or closed position.

3. A loose-leaf holder comprising a back having an arcuate channel portion adjacent 40 its one end, a pivot pin seated therein, a leaf-clamping member having an arcuate channel portion adjacent one of its sides also adapted to directly engage said pivot pin, a cover hingedly connected to the other side of said leaf-clamping member and resilient means for retaining the arcuate channel 45 portions of said back and clamping member in sliding engagement with said pivot pin and the clamping member in either the open or closed position, said arcuate channels of the back and leaf-clamping member having

their rearwardly facing edges spaced apart 55 when said holder is in the leaf holding position, and forced together in abutting relation when said holder is in the extreme open position.

4. In a loose-leaf holder of the character 60 described, a back and a leaf-engaging member each having an arcuate channel formed therein, a pivot pin engaged by each of said arcuate channels, and means for retaining 65 said channels in sliding engagement with said pin, said channels extending but a part way around said pin, concentric therewith and bearing directly upon the periphery thereof and having their edges in abutting 70 relation when said holder is in the open position.

5. A loose-leaf holder comprising a back, a leaf-clamping means supported by said back, a cover hingedly carried by the clamping means, a resilient split tubular member holding said back and leaf clamping means in assembled relation and a shoulder formed across the leaf clamping means intermediate 75 its sides, said shoulder forming a bearing for the holding member and a stop for the cover whereby its opening action is terminated before reaching a position to engage said tubular member.

6. In a loose-leaf holder of the kind described, a back and a leaf clamping member 80 each having an arcuate channel formed along one edge thereof, a pivot pin engaging both channels having a circumference greater than the combined distance across 85 both of said arcuate channels and resilient means for keeping said arcuate channels in engagement with the periphery of said pin.

7. In a loose-leaf holder of the kind described, a back and a leaf clamping member 90 each having an arcuate channel formed along one edge thereof, a pin disposed between the channels and engaging the concave faces of the same, the combined distance across both channels being insufficient 95 to reach around said pin and resilient means for maintaining the channels in sliding engagement with the pin, the adjacent edges of said channels abutting to limit their movement around said pin.

In testimony whereof I hereunto affix my 105 signature this 30th day of June, 1925.

RICHARD M. VAN VALKENBURGH.
